UNITED STATES PATENT OFFICE.

ANDREW JACKSON DOX AND EDWARD SCOTT LORIMER, OF BROOKINGS,
SOUTH DAKOTA; SAID LORIMER ASSIGNOR TO SAID DOX.

HEATING AND COOKING STOVE.

SPECIFICATION forming part of Letters Patent No. 442,111, dated December 9, 1890.

Application filed May 24, 1890. Serial No. 353,057. (No model.)

To all whom it may concern:

Be it known that we, ANDREW JACKSON DOX and EDWARD SCOTT LORIMER, citizens of the United States, residing at Brookings, in the county of Brookings and State of South Dakota, have invented certain new and useful Improvements in Heating and Cooking Stoves; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to stoves, and has for its object the production of a combined heating and cooking stove possessed of great heating capacity and general convenience.

We apply our improvements to wood or coal burning stoves of either the surface-burning or the magazine type, and in case of the former we contemplate the addition of a removable magazine when needed. We gain an increased heating effect by conducting the products of combustion through diving-flues into chambers in the base and thence to the smoke-stack, air being brought into other chambers in the base adjacent to the smoke-passages and conducted up through suitable flues to registers in the sides of the stove-body. We may use either straight diving-flues for the smoke or carry the heated gases around between the double walls of a rear oven.

In the drawings, Figure 1 is a perspective view of a stove, showing one side and the rear. Fig. 2 is a front elevation, partly broken away and in section, on a larger scale. Fig. 3 is a top plan view of the heating-chambers in the base, the top being partly broken away to show the partitions. Fig. 4 is a side elevation, partly in section, of a modified arrangement, showing the ovens.

The body A of a stove may be of any suitable construction. It is provided with the usual feeding-door B, fire-pot C, shaking-grate D, and ash-pit E. Under the bottom of the ash-pit is the heating-box F, which constitutes the base of the stove and is several inches deep. The products of combustion

leave the combustion-chamber on each side through the ports a and pass through horizontal flues G, which extend to the rear of the stove-body and communicate with the diving-flues G', which open into the rear ends of the chambers G². These are U-shaped in plan, as seen in Fig. 3, the bend lying at the front of the heating-box, and the two adjacent legs of the chambers being side by side, separated only by a partition f. At their rear ends these adjacent legs of the chambers G² communicate with the upright smoke-stack G³, which rises between the diving-flues G' behind the stove-body. The course of the smoke is indicated by the undulating arrows. In the upper part of the smoke-stack is an elbow G⁴, communicating directly with the combustion-chamber and provided with a damper, as shown. This connection is for use in starting a fire or in mild weather when a moderate heat is required.

Fresh air is admitted to the heating-box through the air-box H, either from the apartment in which the stove is placed or from the outside of the building, entering the box H through a central neck h. A horizontal deflecting-plate h', suspended midway in the box, compels the air to pass to the sides and ends of the air-box, which is preferably + shaped, as shown. Here the air finds access to the upper part of the box and thence passes through ports h² into the narrow chambers H', located between the legs of the U-shaped smoke-chambers G² in the heating-box. The air here becomes heated by contact with the hot walls of the chambers G², and flows into a narrow chamber H² at the rear of the heating-box, whence it enters the chambers H³ at the sides of the same. In these latter chambers are one or more horizontal deflectors f', arranged as shown in Fig. 4, whereby the air is compelled to circulate back and forth in rising through the chamber. It finally escapes through a port f² in the top of the heating-box into the side flues H⁴, located above the heating-box on either side of the stove-body. From the top of these flues the air enters a space H⁵ between the wall of the stove-body on the outside and the ash-pit and fire-pot on the inside, as clearly shown in Fig. 2. The warm air here

becomes highly heated by contact with the hot fire-pot, and flows out into the room through registers I, which are provided with controlling-handles i. The course of the air 5 is indicated by straight arrows. The fire-pot is fitted snugly to the stove-body at its upper outwardly-flaring edge, and forms an air-tight joint therewith. The heating-box F is provided at its front with doors f³ for removing soot and ashes from the smoke-chambers G². As shown in Fig. 2, a magazine K can be inserted into the top of the stove-body, if desired.

Our arrangements for cooking are as follows: On the outside of each smoke-flue G, near its rear end, is an enlargement g, in the shape of an inverted half-cone, which affords space for the formation of a circular opening g' in the top of the flue and enlargement. 15 This opening is for the reception of cooking utensils, which here receive the full force of the smoke and flame escaping from the stove-body. The opening is provided with a swinging or removable lid g², and may be fitted to receive reducing-rings when small utensils are used. We also contemplate using a rear double-walled oven L, supported on brackets l, or in any suitable manner. The diving-flues G' in this case are provided with 20 elbows g³ near top and bottom and with a damper g⁴ midway between them. The upper elbow communicates with a chamber l', extending between the double walls of the oven, over the top, down at the back and at 25 one end, and under the bottom to the lower elbow, whereby the products of combustion are compelled to pass almost entirely around the oven. When the oven is not in use, the damper g⁴ can be opened and the smoke permitted to pass directly through the diving-flues. 30

In the top plate of the outer wall of the oven are formed holes 12 for additional cooking utensils. We may also make the stove-body tall enough to accommodate an oven M in the upper part of it above the feeding-door B.

The oven consists of a cylindrical box having handles m attached to its top, whereby it 35 can be let down into the stove or lifted out, the top A' of the stove-body being removable. The oven rests on lugs or ears or a projecting flange a' on the inside of the stove-body. It has a door m' in one side that registers 45 with a door B' in the stove-body, by which access is had to the oven when in use. The flange a' affords a convenient support for a magazine in case it is desired to use one. The oven M being lifted out, the magazine is 55

dropped down into the stove, suitable projections on the outside of the magazine resting upon the flange, as indicated in dotted lines. 6

Instead of removing the entire oven, it may be provided with a removable top and bottom, and the magazine when inserted will 6 rest upon the inwardly-projecting flange around the lower edge of the oven, on which its removable bottom is supported when in place.

Having thus described our invention, what 7 we claim, and desire to secure by Letters Patent, is—

1. A stove having a base composed of a heating-box containing smoke-chambers and air-passages H' H² H³, the latter having the 7⁵ deflectors f', and the side flues H⁴, located above the heating-box and delivering air to the spaces H⁵ between the fire-pot and the stove-body, substantially as described.

2. A stove having a base composed of a 8⁰ heating-box containing smoke-chambers and air-passages, and an air-box underneath the heating-box, provided with a horizontal deflecting-plate and communicating with the air-passages in the heating-box, substantially 85 as described.

3. The combination, with the heating-box F, of the air-box H, having the central neck h, the horizontal deflector h', and ports h², communicating with the air-passages H' in 90 the heating-box, substantially as described.

4. The combination, with a stove, of the heating-box F, having the U-shaped smoke-chambers G² and the air-passages H' H² H³ alternating therewith, the air-box H, having 95 a deflector h', the deflectors f' in the chamber H³, the side flues H⁴, and the registers I, substantially as described.

5. The combination, with a stove-body, of the horizontal flues G, the diving-flues G', provided with elbows g³ and dampers g⁴, the oven L, having a space l' between its double walls communicating with the diving-flues, a heating-box F, and smoke-stack G³, substantially 100 as described.

6. The combination, with a stove-body having the internal flange a', of a removable oven and a removable magazine for fuel, either one of which can be inserted into the stove and rest upon the flange a', substantially as described.

In testimony whereof we affix our signatures in presence of two witnesses.

ANDREW JACKSON DOX.
EDWARD SCOTT LORIMER.
